UNITED STATES PATENT OFFICE.

ELIAS L. ELLIOTT, OF LAKEWOOD, OHIO, AND EUGÈNE LUCIEN, OF PARIS, FRANCE.

ILLUMINATED SIGN.

No. 805,853.

Specification of Letters Patent.

Patented Nov. 21, 1905.

Application filed September 16, 1904. Serial No. 224,684.

To all whom it may concern:

Be it known that we, ELIAS L. ELLIOTT, a citizen of the United States, residing at Lakewood, in the county of Cuyahoga and State 5 of Ohio, and EUGÈNE LUCIEN, (Marquis Carlet de la Roziere,) a citizen of the French Republic, residing at Paris, in the Republic of France, have invented a certain new and useful Improvement in Illuminated Signs, of 10 which the following is a full, clear, and exact description, reference being had to the accompanying drawings.

The object of this invention is to provide in a very simple form an illuminated sign attractive in appearance and one which shall require a minimum of electric current for its lighting. In accomplishing this we form a sign of reflecting-letters placed in rows, each row being forward of the one inside 20 thereof, and the surface of the forward rows being of increasing inclination toward the axis, whereby the rows as a whole form an interrupted concave mirror. At the focus of this mirror we place an electric lamp whose rays 25 are reflected by the letters composing the sign. Our invention comprises such an illuminated sign, and the invention is more fully hereinafter described, and its essential characteristics are set out in the claims.

30 In the drawings, Figure 1 is a front view of the sign, and Fig. 2 is a vertical section therethrough.

Referring to the parts by letters, A represents any suitable standard or fixture carrying 35 a supporting-surface B, which is preferably of the form of a parabola in section. This surface may be conveniently made of wire-netting. Secured to the support B are the letters C, which constitute the sign. These 40 letters are made of reflecting material and may be placed in concentric rows around the axis of the parabola. A single incandescent electric lamp D is placed at the focus of the parabola, and its rays passing to the letters C are reflected 45 forward in parallel lines. An opaque

shield E is placed in front of the lamp, and the surface of the support B between and around the letters is painted black to prevent the reflection from any surface but the letters. By this means the illuminated letters will be the 50 only part of the device visible at night from a little distance away, and a very pleasing effect is produced. The rear side of the shield is preferably made reflecting to return the forward rays from the lamp to the reflecting- 55 letters.

We claim—

1. In an illuminated sign, a support carrying the letters forming the sign, the surfaces of the letters being approximately parabolic, a light for illuminating the letters disposed at the focus of the parabolic surfaces in such manner as to illuminate the letters and cause the rays of light reflected therefrom to be thrown forward. 60

2. In an illuminated sign, a support carrying letters, said letters being concaved so as to present an approximately parabolic surface, a light for illuminating the sign placed at approximately the focus of the parabolic 70 surfaces of the letters in such manner as to cause the rays of light reflected from the letters to travel forward and a shield placed in front of the light in order to prevent it from being normally visible. 75

3. In an illuminated sign, a concave support carrying letters in such manner as to present an approximately parabolic surface, and a light for illuminating the sign placed substantially at the focus of the parabolic curve, 80 all arranged in such manner as to cause the reflected rays to travel forward in approximately parallel lines.

In testimony whereof we hereunto affix our signatures in the presence of two witnesses. 85

ELIAS L. ELLIOTT.
EUGÈNE LUCIEN.
